UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

STITCH-FORMING MECHANISM FOR SEWING-MACHINES.

1,366,476.

Specification of Letters Patent. Patented Jan. 25, 1921.

Application filed March 29, 1918. Serial No. 225,488.

To all whom it may concern:

Be it known that I, JAMES R. MOFFATT, a citizen of the United States, residing at Chicago, in the county of Cook, State of Illinois, have invented certain new and useful Improvements in Stitch-Forming Mechanism for Sewing-Machines, of which the following is a description, reference being had to the accompanying drawing and to the figures of reference marked thereon.

The invention relates to new and useful improvements in stitch forming mechanisms for sewing machines and more particularly to a stitch forming mechanism having devices adapted to join the meeting edges of fabric sections and for covering the meeting edges thereof.

An object of the invention is to provide a stitch forming mechanism of the above character wherein the fabric sections being stitched are supported by a cylindrical work support and wherein said fabric sections are fed onto the work support underneath the overhanging arm carrying the stitching elements located above the work support, and wherein said stitching elements are arranged so as to provide ample clearance space underneath the arm for the handling of the fabric sections.

30. A further object of the invention is to provide a machine of the above character wherein the edges of the fabric sections to be joined are trimmed prior to the stitching of the same by horizontally disposed trimming devices and wherein the lines of stitching are joined by a cross thread which covers the upper surface of the meeting edges of the fabric sections.

40. A still further object of the invention is to provide a stitching mechanism of the above character wherein the movable trimming blade and the thread hook for laying the cross thread, are both operated from a single eccentric.

45. These and other objects will in part be obvious and will in part be hereinafter more fully disclosed.

50. In the drawings which show by way of illustration one embodiment of the invention:

Figure 1 is a side view of a machine embodying my invention;

Fig. 2 is a front elevation of the parts located at the front end of the machine, showing the work supporting cylinder in 55 end view;

Fig. 3 is an enlarged view of the front end of the machine as viewed from the same side as in Fig. 1 with the work support broken away to show the looper and the 60 trimming lever broken away to show the cross thread laying mechanism;

Fig. 4 is an enlarged view of the opposite side of the machine, with the work support broken away to show the looper 65 and a part of the feeding mechanism, the presser foot also being in section;

Fig. 5 is a sectional view on the line 5—5 of Fig. 4, the tension for the cross thread being omitted;

Fig. 6 is a sectional view on the line 6—6 of Fig. 1; and

Fig. 7 is a view showing the relation of the fabric sections to the stitching and covering threads.

The invention is especially adapted for a sewing machine having a standard carrying a cylindrical work support and an overhanging arm which is parallel with and overhangs the work support. The fabric sections to be joined are fed onto the work support and in a direction parallel with the longitudinal axis thereof. The edges to be joined are turned out of the plane of the fabric sections and are trimmed by horizontally disposed trimming members, after which they are preferably slightly overlapped and they are then joined by a three needle stitching mechanism, the center needle only, passing through the overlapped 90 fabric sections. Coöperating with the needles beneath the work support, is a single looper and coöperating with the needles above the work support, is a thread hook and thread finger, which lays a cross thread 95 in loops for the needles to enter. Thus the cross thread joins the lines of stitching and covers the edges of the joined fabric sections. The stitch forming elements are all operated from a cross shaft at right angles 100 to the work support. The movable blade of the trimming mechanism and the thread hook are both operated from a single eccentric on the cross shaft and the connections

between this eccentric and the hook and trimming blade are so disposed as to give ample clearance room for the handling of the fabric sections underneath the work supporting arm.

Referring more in detail to the drawings, I have shown my invention as applied to a machine having a supporting base 1, carrying a standard 2, on which is mounted 10 an overhanging arm 3. Projecting from the standard 2 is a cylindrical work supporting arm or bed 4. This work supporting arm is located directly underneath the overhanging arm and is parallel therewith. Mounted 15 to reciprocate in the outer end of the overhanging arm 3 is a needle bar 5 carrying three needles 6, 7 and 8. This needle bar is reciprocated by a needle lever 9 which is connected to a link 10, which in turn is connected to the needle bar. The needle lever 9 is oscillated by suitable means from the main shaft indicated in dotted lines at 11 in Fig. 1 of the drawings. This main shaft lies in a plane at right angles to the longitudinal axis of the work support.

Coöperating with the three needles beneath the work support, is a threaded looper 12. This looper is carried by a looper supporting shaft 13, which is also operated by 30 suitable connections with the main shaft 11.

The fabric sections are fed onto the work supporting arm and in a direction parallel with its longitudinal axis by a feeding mechanism which includes feed dogs 14. 35 These feed dogs have their teeth arranged so as to feed the material onto the work supporting arm and said feed dogs are operated by suitable connections with the main shaft 11. Machines of this type are well known in 40 the art and it is not thought that further detail description thereof is necessary.

The material is held on the work support by a presser foot 15. This presser foot is carried by a presser bar 16 mounted in the 45 overhanging arm. This presser bar 16 is connected by a pin 16^a to a collar 16^b on the presser guide bar 16^c. The presser bar is forced downwardly by a flat spring 17, and which bears against a pin 19 fixed to 50 the guide bar 16^c. The presser bar is raised by a lever 18 which engages the pin 19 on the presser guide bar. The presser foot is formed with a guiding slot 20 which leads from the extreme front end thereof in the 55 line of feed and terminates just in front of the needle opening 21, which receives the three needles 6, 7 and 8. Mounted in a recess in the presser foot is a fixed trimming blade 22. Coöperating with this fixed trimming blade 22 is a movable trimming blade 23. Said movable trimming blade is carried by 60 a lever 24. At the end of the lever 24 is a vertically adjustable block 24^a to which the blade 23 is clamped. The inner end of the 65 fixed blade 22 preferably terminates at the

side wall of the guiding slot 20, while the movable blade 23 moves across the guiding slot and trims the upturned edges of the fabric sections which are directed into the guiding slot. The work supporting arm is 70 formed with a V-shaped guide 25 which assists in directing the upturned edges of the fabric sections. The presser foot is preferably so constructed that the edges of the fabric sections after they are trimmed, are 75 brought back into overlapped relation as shown diagrammatically in Fig. 7 of the drawings. In this figure of the drawings, I have indicated the fabric sections at F and F', the needle threads for the needles 6, 7 80 and 8 respectively, at 6', 7' and 8', the looper thread at l and the cross thread at c. It will be noted that the fabric sections are so disposed that the central needle 7 passes through the overlapped edges, while the 85 needle 6 passes at one side of the overlapped edges and the needle 8 on the other side thereof. The cross thread c and looper thread l cover the edges of the joined fabric sections. 90

The lever 24 is mounted to swing about a guide bar 26, which in turn is mounted in the overhanging arm and is connected to an arm 27 projecting from the presser foot. Said lever 24 has a forked bearing and the arm 27 extends between the members of the fork. This connection holds the lever from sidewise movement on the bar 26. Said arm 27 is connected to the bar 26 by a set screw 28. The lever 24 is not adjustable 100 sidewise and the movable trimming blade is adjusted vertically by shifting the block 24^a. Preferably formed integral with the arm of the lever carrying the trimmer blade 23, is an arm 29 which serves to oscillate the lever. This arm 29 carries a ball stud 30 to which a link 31 is attached. The link 31 in turn is connected to a lever 32, which is fulcrumed at 33 on the overhanging arm. Mounted in the forward end of the overhanging arm is a cross shaft 34. This cross shaft 34 carries an upwardly extending arm 35. Pivoted to this upwardly extending arm 35 at 36 is a link 37. Said link in turn is pivoted at 38 to the lever 32. The cross 110 shaft 34 is operated by a link 39 which is pivoted at 40 to the arm 35 on the cross shaft 34. The other end of the link 39 is pivoted to a lever 41, which is fulcrumed at 42 on a lug 43 carried by the standard. 120 The lower end of the lever 41 is pivoted at 44 to an eccentric strap 45, which coöperates with an eccentric 46 on the main shaft 11. As the main shaft rotates, the eccentric 46 will oscillate the lever 41 and through the 125 link 39 oscillate the cross shaft 34 and through the link 31 oscillate the lever 24 carrying the movable trimmer blade 23.

The cross thread indicated at c in the drawings is laid in loop form for the ne- 130

dles by a thread hook 47 and a coöperating thread finger 48. The hook 47 is carried by a lever 49 which is mounted to turn about the presser bar 16 as an axis. Said hook 47 5 has an upwardly extending shank 50 which is mounted in the outer end of one arm of the lever 49. The other arm of the lever 49 is pivoted at 51 to a link 52. The link 52 is in turn pivoted to a downwardly extending arm 10 53 carried by the cross shaft 34. As the cross shaft oscillates through the movements of the link 39, this arm 53 will be oscillated and this will in turn oscillate the lever 49 carrying the thread hook 47. The 15 thread finger 48 is provided with a shank 54 which is mounted in an arm 55 carried by a collar 56. The collar 56 is clamped to a split sleeve 57 by a clamping screw 58. The lever 49 swings freely on this collar. 20 The specific mounting of the cross thread laying hook and the finger, forms no part of the present invention, but is shown, described and claimed in my copending application, Serial Number 220,046, filed March 2, 1918. 25 The cross thread *c* passes through a thread guide 59 carried by the needle clamp 60 at the lower end of the needle bar 5. This thread guide 59 moves up and down with the needle bar. The cross thread *c* also passes 30 through a tension 61 mounted on the overhanging arm. The thread finger 48 is shaped and positioned relative to the guide 59 so that when the guide is at the lower end of its stroke and the needles are clear down, 35 the cross thread will be moved forward on the finger and positioned so that the thread hook as it moves forward, will engage said cross thread. As the hook continues its forward movement, the thread guide 59 moves 40 upwardly and the pull of the hook on the thread will cause the thread to slide back on the finger and be properly positioned, so that the needles 6 and 7 will straddle the thread and thus the cross thread is stitched 45 to the fabric sections. This particular shaping of the thread finger and the relation of the same to the movable cross thread hook and the movable thread guide on the needle bar, are shown, described and claimed in 50 my copending application, Serial Number 181,208, filed July 18, 1917.

A combined cover and deflecting plate 62 is pivoted at 63 to an arm 64 extending outwardly from the presser foot and this cover plate 62 covers the thread hook and extends 55 across the movable trimming blade just in rear of the point of trimming, so that the trimmed off strip is deflected away from the stitching mechanism.

60 From the above it will be noted that the movable trimming blade and the thread hook are both operated from a single eccentric and through a series of levers and connecting links, the proper timing and stroke 65 of these devices are obtained.

It is obvious that minor changes in the details of construction and the arrangement of parts, may be made without departing from the spirit of the invention as set forth in the appended claims.

70

Having thus fully described my invention, what I claim is new and desire to secure by Letters Patent is:—

1. A sewing machine including in combination, a standard, a cross shaft, a work 75 supporting arm projecting from the standard, an overhanging arm carried by the standard, stitch forming mechanism including a cross thread laying device, horizontally disposed trimming blades located in 80 front of the stitch forming mechanism, one of said blades being movable, an eccentric on the cross shaft, a rock shaft carried by the overhanging arm, means for oscillating the rock shaft from said eccentric, an arm 85 on said rock shaft and devices actuated thereby for oscillating said thread laying device, and a second arm on said rock shaft and devices actuated thereby for oscillating the movable trimming blade. 90

2. A sewing machine including in combination a standard, a cross shaft, a work supporting arm projecting from the standard, an overhanging arm carried by the standard, stitch forming mechanism including a cross thread laying device, horizontally disposed trimming blades located in 95 front of the stitch forming mechanism, one of said blades being movable, an eccentric on the cross shaft, a rock shaft carried by the overhanging arm, means for oscillating the rock shaft from said eccentric, an arm at one end of said rock shaft and devices actuated thereby for oscillating said thread laying device, an arm at the other end of 100 said rock shaft and devices actuated thereby for oscillating the movable trimming blade. 105

3. A sewing machine including in combination a standard, a cross shaft, a work supporting arm projecting from the standard, an overhanging arm carried by the standard, stitch forming mechanism including a cross thread laying device, horizontally disposed trimming blades located in 110 front of the stitch forming mechanism, one of said blades being movable, an eccentric on the cross shaft, a rock shaft carried by the overhanging arm at the forward end thereof, said rock shaft having an upwardly 115 extending arm, a lever carried by the standard at the rear end of the overhanging arm, means connected to the lower end of said lever for oscillating the same from said eccentric, a link for connecting the upper end of said lever with the arm projecting upwardly from the rock shaft and devices actuated by said rock shaft for oscillating the thread laying device and for oscillating the movable trimming blade. 120

60 From the above it will be noted that the movable trimming blade and the thread hook are both operated from a single eccentric and through a series of levers and connecting links, the proper timing and stroke 65 of these devices are obtained.

4. A sewing machine including in combi- 130

nation a standard, a cross shaft, a work supporting arm projecting from the standard, an overhanging arm carried by the standard, stitch forming mechanism including a cross thread laying device, horizontally disposed trimming blades located in front of the stitch forming mechanism, one of said blades being movable, an eccentric on the cross shaft, a rock shaft carried by 5 the overhanging arm at the forward end thereof, said rock shaft having an upwardly extending arm, a lever carried by the standard at the rear ends of the overhanging arm, means connected to the lower end of 10 said lever for oscillating the same from said eccentric, a link for connecting the upper end of said lever with the arm projecting upwardly from the rock shaft, an arm carried by one end of the rock shaft 15 and depending therefrom, devices actuated by said last named arm for actuating the thread laying device, a lever mounted on the overhanging arm, a link connected with the arm on the rock shaft extending upwardly therefrom and to said lever for oscillating the lever and a link to the lower 20 end of said last named lever and to the 25

movable trimming blade for oscillating the same.

5. A sewing machine including in combination a standard, a cylindrical work supporting arm projecting therefrom, an overhanging arm, means for feeding the material longitudinally of the arm, a presser foot, a presser bar supporting the same, a 30 fixed horizontal trimming blade carried by the presser foot, a movable horizontal trimming blade coöperating with the fixed blade, a lever carrying said movable trimming blade, a bar mounted for vertical movement 35 in the head and connected to the presser bar for supporting said lever, a lever mounted on the overhanging arm and having a link connection with the lever carrying the trimming blade, a cross shaft in the standard and means actuated by the cross shaft 40 for oscillating the last named lever.

In testimony whereof, I affix my signature, in the presence of two witnesses.

JAMES R. MOFFATT.
